US00D804430S

(12) **United States Design Patent** (10) **Patent No.:** **US D804,430 S**
Besana et al. (45) **Date of Patent:** **** Dec. 5, 2017**

(54) **CIRCUIT BREAKERS**

(71) Applicant: **ABB S.p. A.**, Milan (IT)

(72) Inventors: **Stefano Besana**, Terno d'Isola (IT);
Lucio Azzola, Bergamo (IT)

(73) Assignee: **ABB S.p.A.**, Milan (IT)

(**) Term: **15 Years**

(21) Appl. No.: **29/561,373**

(22) Filed: **Apr. 15, 2016**

Related U.S. Application Data

(62) Division of application No. 29/489,919, filed on May 5, 2014, now Pat. No. Des. 757,659, which is a division of application No. 29/459,135, filed on Jun. 26, 2013, now Pat. No. Des. 707,636, which is a division of application No. 29/383,747, filed on Jan.

(57) **CLAIM**

The ornamental design for circuit breakers, as shown and described.

DESCRIPTION

FIG. 1 is a perspective view of a first embodiment of the new design;

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof;

FIG. 8 is a perspective view of a second embodiment of the new design;

FIG. 9 is a front view thereof;

FIG. 10 is a rear view thereof;

FIG. 11 is a top view thereof;

FIG. 12 is a bottom view thereof;

FIG. 13 is a left view thereof; and,

FIG. 14 is a right view thereof.

Broken lines in the drawings form no part of the design to be patented.

1 Claim, 14 Drawing Sheets
